PORTABLE WORK STATION

Henry H. Lott, 1225 St. James Ave., Orange, Calif.

Filed July 21, 1964, Ser. No. 80,942

Term of patent 14 years

(Cl. D55—1)

FIGURE 1 is a perspective view of a portable work station showing my new design;

FIGURE 2 is a front elevational view thereof;

FIGURE 3 is a rear elevational view of such work station;

FIGURE 4 is a top plan view thereof; and

FIGURE 5 is a sectional view, on a reduced scale, taken substantially along line 5—5 of FIGURE 2.

I claim:

The ornamental design for a portable work station, substantially as shown.
